UNITED STATES PATENT OFFICE.

FRANK L. O. WADSWORTH, OF PITTSBURGH, PENNSYLVANIA, ASSIGNOR TO ALBERT KINGSBURY, OF PITTSBURGH, PENNSYLVANIA.

BEARING.

Application filed June 1, 1918. Serial No. 237,740.

To all whom it may concern:

Be it known that I, FRANK L. O. WADSWORTH, a citizen of the United States of America, and a resident of Pittsburgh, Allegheny County, and State of Pennsylvania, have invented certain new and useful Improvements in Bearings, of which the following is a specification, reference being had to the accompanying drawings, forming a 10 part thereof.

My invention relates to bearings, and more particularly to means for equitably distributing the pressure on the bearing surfaces. It has special reference to thrust 15 bearing constructions of the Kingsbury flexible shoe type which comprise annularly arranged series of bearing segments capable of both tangential or longitudinal and radial or transverse tilting movements,—as illustrated and described, for example, in Kingsbury Patent No. 947,242.

One object of my invention is to provide simple and effective equalizing means of 20 novel construction for the equitable automatic distribution of the load or end thrust over the entire surface of bearing engagement between the relatively fixed and movable members of the structure.

A further object of this invention is to 25 provide a structure in which the equitable distribution of the load is effected by automatic radial movements of load supporting parts, preferably so arranged as to permit the larger part of the load or end thrust 30 to be carried by relatively rigid members and to leave only a small component of the load to be borne by the instrumentalities effective in producing the radial equalization movements.

Another object is to provide a structure 35 of the aforesaid character in which the automatic equalization shall be either directly or indirectly effected by the centrifugal action of rotating parts when the bearing is 40 in operation.

In order that my invention may be 45 thoroughly understood I will now proceed to describe the same in the following specification and will then point out the novel 50 features thereof in appended claims.

The invention is capable of receiving a 55 variety of mechanical expressions some of which are shown on the accompanying

drawings, but it is to be expressly understood that the drawings are for the purpose 55 of illustration only and are not to be construed as a definition of the limits of the invention, reference being had to the appended claims for that purpose.

Automatic equalizers for thrust bearings 60 heretofore employed are characterized by a yielding support which is arranged to permit the bearing members to move substantially parallel to the bearing axis or direction of thrust and adjust themselves to such 65 positions that each carries its proper portion of the load.

The nature of my improved equalizing means can be best understood by first referring briefly to the two general types of 70 automatic equalizers now in use. In one of these types the bearing segments are tiltably mounted on what may be termed a ball and socket ring support which may be constructed in a number of different forms, but 75 which is characterized by a rocking movement about two axes at right angles to each other, whereby the plane of bearing engagement is permitted to assume any angle to the axis of rotation of the bearing members. In the second of the above-mentioned 80 types the bearing segments are flexibly supported on, or by, a circumferentially elastic or circumferentially yielding ring structure and this has also been developed in a number 85 of different forms, all of which are characterized by a relative yielding or flexing movement of different circumferential portions of the ring whereby the supports for the bearing segments are permitted to move 90 up or down—or more generally stated, toward or away from—the plane of the co-operating bearing surface. In both of these types of equalizer construction the only substantial movement of the engaging surfaces 95 which results from the action of the equalizing means is one which is substantially or nearly at right angles to the plane of bearing engagement; or in general substantially parallel to the axis of rotation of the bearing. 100

In accordance with my present invention the equalization, or equitable distribution, of the thrust pressures over the bearing surfaces is effected primarily by a relative radial movement—as contrasted with an end- 105

wise or axial movement—either of the different bearing shoes or segments, or of the pivotal supports therefor, whereby each of those segments is independently and automatically adjusted to bear with the desired degree of pressure against the cooperating surface of the opposed bearing member.

Referring to the drawings:

- Figure 1 is a sectional elevation, on the line 1—1 of Figure 2, of a bearing structure constituting one embodiment of my invention and provided with an automatic equalizer or pressure distributor arranged and constructed in accordance therewith.
- 15 The bearing shoes or segments in this structure are mounted on pivoted rockers.

Figure 2 is a sectional plan view on the line 2—2 of Figure 1.

- 20 Figure 3 is an elevation showing a single shoe and its support taken on the line 3—3 of Figure 1.

Figure 4 is a sectional elevation showing a portion of a structure which is a slight modification of that shown in Figure 1.

- 25 Figure 5 is a sectional plan view on the line 5—5 of Figure 4.

- 30 Figure 6 is a sectional elevation showing a portion of another embodiment of my invention, the view corresponding to that portion of Figure 1 which is on the right-hand side of the shaft.

- 35 Figure 7 is a sectional elevation of another bearing structure which constitutes an embodiment of my invention and in which the bearing surfaces are spherically curved and the shoes are mounted on bearing balls.

Figure 8 is a sectional elevation showing a detail of the Figure 7 structure and taken on the line 8—8 of Figure 7.

- 40 Figure 9 is a view corresponding to the right-hand portion of Figure 7 and illustrates an embodiment of my invention in which the bearing surfaces are plane.

- 45 Figure 10 is a transverse section of the structure shown in Figure 9.

- Figure 11 is a sectional elevation of another bearing structure which embodies my invention and in which the bearing shoes or segments form parts of the rotatable member of the bearing.

Figure 12 is an elevation showing a portion of a bearing which constitutes a slight modification of that shown in Figure 11.

- 55 Figure 13 is a sectional detail view taken on the line 13—13 of Figure 12.

Figure 14 is a sectional elevation of a horizontal thrust bearing which constitutes an embodiment of my invention.

- 60 Figure 15 is a transverse sectional elevation on the line 15—15 of Figure 14.

Figure 16 is a partial section of a slightly modified arrangement corresponding to the upper left-hand portion of the structure shown in Figure 14.

- 65 Figure 17 is a view corresponding to Fig-

ure 14 of another embodiment of my invention, the shoes being individually counterbalanced, and

Figure 18 is a partial sectional elevation taken on the line 18—18 of Figure 17. 70

Figure 19 is a sectional elevation of a vertical shaft bearing embodying my invention, the bearing shoes being supported on conically curved rollers.

Figure 20 is a sectional plan view on the line 20—20 of Figure 19 with certain of the shoes broken away to show their supports. 75

Figure 21 is a sectional elevation on the line 21—21 of Figure 19.

A slight modification of the same structure is shown in Figure 22 which is a sectional elevation corresponding to the left-hand portion in Figure 19. 80

Figures 23 and 24 are detail views showing, in side and end elevation, a rocker which may be substituted for the rollers of Figures 19 to 22. 85

Figure 25 is a view corresponding to Figure 19 of another structure in which bearing balls are utilized in place of the rollers or rockers of Figures 19 to 24. 90

Figure 26 is a partial plan view of the structure shown in Figure 25, and

Figure 27 is a sectional view developed into one plane and taken on the line 27—27 of Figure 26. 95

Figure 28 is a sectional elevation on the line 28—28 of Figure 29 and discloses an embodiment of my invention in which the bearing shoes are made in two parts or sections to permit the radial tilting of the top section relative to the bottom section which is mounted on conical rollers. 100

Figure 29 is a partially sectional plan view of the structure shown in Figure 28 with certain of the shoes omitted to show the rollers on which the lower part of each shoe is mounted. The top section of certain other shoes is removed to show the formation of the engaging surfaces between sections. 105

Figure 30 is a sectional elevation, developed into one plane, of the structure shown in Figure 29.

Figure 31 is a sectional elevation of a portion of another bearing structure constituting a slight modification of that shown in Figure 28. 115

Figure 32 is a sectional elevation of the structure shown in Figure 31. 120

Figure 33 is a sectional elevation of half of a bearing structure which embodies my invention and in which the bearing shoes are made in two parts having cooperating inclined surfaces. 125

Figure 34 is a sectional elevation on the line 34—34 of Figure 33.

Figure 35 is a view on the right-hand side of the shaft of a structure which is a slight modification of that shown in Figure 130

33, the two-part shoe constituting a member of the rotating part of the bearing.

Figure 36 is a view corresponding to Figure 33, of another embodiment of my invention.

Figure 37 is a plan view on the line 37—37 of Figure 36.

Special reference may first be had to Figures 1 to 3 in which 1 designates a base or foundation having an opening through which a shaft 2 extends, the shaft being provided with a thrust block 3 and thrust collar 4. In the form shown, the base has a sleeve 5 which extends close to the shaft 15 and cooperates with a housing 6 to form an oil well 7 in which the parts of the bearing are disposed. The thrust collar 4 extends into the oil chamber so that its bearing surface 8 is submerged.

Cooperating with the bearing surface 8 are a plurality of bearing segments or shoes 9, each of which is mounted on an outwardly inclined rocker 10. Each rocker is mounted on a pivot pin 11 supported by bearing blocks 15 or plates which form parts of the base ring 1.

A guide ring 12 is mounted on the base ring 1, loosely surrounds the bearing shoes, and has lugs 13 which extend inwardly between the shoes and prevent their rotation.

The inclination of the rockers 10 is such that the shoes tend to move outwardly and downwardly under the influence of the thrust pressure, but this tendency is opposed by springs 14 which extend into spring pockets 15 in the shoes and press the shoes radially inward. The springs react on a spring equalizing ring 16 which is freely mounted on the top of the ring 12.

The bottom surface, or at least a portion of the bottom surface, of each shoe is radially inclined and circumferentially curved to cooperate with the top of the rocker which is spherically curved and preferably has a dowel pin or projection 17 which cooperates with a suitable recess in the bottom of the shoe.

The shoes are thus mounted to tilt tangentially with respect to the shaft so as to establish and maintain a film of oil at the bearing surfaces, and are furthermore free to tilt radially so as to equalize the pressure on all portions of the bearing surface, in accordance with the principles of the Kingsbury bearings. The dowel pins 17 prevent the shoes from slipping on the spherical surface of the rockers, and insure a true rolling movement between the engaging parts.

The load or pressure on the bearing surfaces is also equitably distributed or equalized by the tendency of the shoes 9 to move outwardly and downwardly, i. e. radially, under excess pressure, which movement is opposed by the corresponding springs 14 and the tensions of said springs

are equalized among themselves by the equalizing ring 16. At the same time the major portion of the load is borne by the rigid rockers 10 and only a relatively small radial component of the load is borne by the flexible or resilient instrumentalities which effect the equitable distribution of the pressure.

If the spherical surface at the outer end of the rocker has a short radius of curvature, the bottom surface of the shoe is not necessarily inclined, the rocker in that case acting like a link and tending to carry the shoe outward and downward even though the bottom surface of the shoe is parallel to the bearing surface.

This embodiment of my invention is shown in Figure 4. Each segment or shoe in this case is provided with an insert 18, which may be formed of hardened steel, for example, and which has a socket or recess with which the outer end 19 of the rocker 20 cooperates. In the form here shown, the body of the rocker has the form of a cylinder with end flanges 21 and is mounted in a grooved block 22 on the base 1. The springs 23 in this arrangement react upon a rigid flange 24 of the base, instead of upon a spring equalizer ring.

On the other hand, if the bottom surface of the shoe is inclined the end of the rocker may have the shape of a segment of a sphere as shown in Figures 1 to 3, or a ball or other spherical support may be substituted as employed in some of the embodiments (see Figure 9) hereinafter explained.

The springs are obviously only subjected to a small proportion of the thrust pressure to which the shoes are subjected, but they nevertheless constitute a yielding means for holding the shoes in such positions as to equalize the thrust pressure upon them.

It is not essential that the rockers shall incline radially outward as shown in Figures 1 to 5, as they may, for example, be inclined inwardly as shown in Figure 6. The rockers are here designated 25 and they are pressed outwardly by the springs 26 which react on a freely mounted spring equalizer ring 27 corresponding to the ring 16. The tendency due to the thrust pressure is, to force the rockers inwardly in opposition to the springs 26, the inclined surface of each segment or shoe tending to slide outwardly on the spherically curved outer end of its rocker. The springs accordingly serve as before to automatically equalize the pressure on the several shoes.

The shoes are limited in their radial outward movement by lugs 28 on a guide ring 29 which corresponds to the ring 12, and is similarly provided with lugs 13.

In the form shown in Figures 7 and 8, in which corresponding parts are designated

by the same reference characters—a thrust collar 30 is substituted for the thrust collar 4 and is provided with a spherically curved thrust surface 31. The bearing segments or shoes 32 are provided with cooperating bearing surfaces and are mounted on bearing balls 33.

The bottom surface of each shoe is preferably provided with a hardened block 34 having a cylindrical groove which extends radially to receive and cooperate with the bearing ball 33.

The inclination of the bearing surfaces, although curved, is such that the thrust pressure tends to force the shoes outwardly and this tendency is opposed by springs 14^a cooperating with a spring equalizer ring 16^a.

The bearing balls 33 are mounted in suitable sockets in the base ring and may desirably be supported on a plurality of small balls 35. In this arrangement, as in those above described, the thrust pressure is largely borne by the ball bearing supports which cannot yield vertically, while only a comparatively small proportion of the load is taken up by the radially yielding equalizing means—the ring 16^a and the springs 14^a—which may therefore be made comparatively light.

Figures 9 and 10 show an embodiment of my invention in which the annular bearing members may be united into a single flexible ring structure since the equalization is effected independently of any radial movement of the bearing segments or shoes themselves.

The segments, which are designated 36, have inclined bottom surfaces preferably provided with hardened inserts 37 which may be radially grooved to cooperate with wedge elements which take the form of bearing balls 38 on which the shoes are supported. Each shoe is held against radial movement by a ring 39 and in order to reduce the resistance to tilting movements each shoe is preferably provided with a spherical lug 40 which cooperates with the surface of said ring.

The arrangement is such that the thrust pressure tends to force the bearing balls 38 inwardly and they are free to move radially in the grooves 41 except for the springs 42 which react on a spring equalizer ring 43 and press them radially outward.

It is evident that in this arrangement the bearing member may either be in the form of independent shoes or a flexible ring structure of any suitable form such as a plurality of segments which are joined, as shown in Figure 10, by flexible webs or connectors 44. In fact, this equalizing arrangement is applicable to either rigid or flexible thrust collars, the bearing balls being forced into such positions as will equalize the pressure upon the bearing surfaces of the annular

bearing members whatever their form may be.

The individual shoe structure or the flexible ring structure presents, of course, all the operative characteristics—both as regards 70 automatic lubrication and transverse tilting of the segmental bearing surfaces—which distinguish the Kingsbury bearings.

Referring to Figures 11, 12 and 13, it is evident that the arrangement of radially yielding pressure-distributing or equalizing means is applicable to the rotatable as well as the stationary member of the bearing, in which event centrifugal force may be utilized as the means whereby to oppose 80 radial movement of the bearing elements under the radial component of the bearing pressure. In the arrangement here shown 45 designates the base of a foot-stop bearing having a spherical seat 46 in which a relatively stationary thrust block 47 is mounted. 48 designates a vertical shaft, having a thrust collar 49 which is provided with an inclined annular or beveled surface 50, and a flange 51. A plurality of bearing segments or shoes 52, provided with spherically faced buttons 53, are mounted on the beveled surface 50 within the flange 51. The back surfaces of the shoes may desirably be shaped to correspond, in general, to the adjacent surface of the thrust collar, although this is not essential. In any event, the arrangement is such that the thrust pressure tends to force the shoes inwardly on the inclined surface 50; and when the bearing 100 is at rest the shoes will be forced against the adjacent face of the shaft 48.

When the bearing is in operation the proper spaced relation between the shoes is maintained by the flange 51 which has lugs 105 54 that extend between shoes and cause them to rotate with the thrust collar. The centrifugal force set up by their rotation causes the shoes to move outwardly into such positions as to substantially equalize 110 the pressure upon the several shoes.

In order to assist in the maintenance of the desired equalization at various speeds, and in order to guard against the interference of the equalization action by the physical contact of the outwardly moving shoes with the flange 51, springs 55 are preferably provided to oppose and restrict the effect of the centrifugal action.

In this case the springs do not act equally 120 to distribute the pressure on the shoes, this result being accomplished by the centrifugal force which constitutes the means for maintaining the shoes in their proper positions. The springs oppose the centrifugal 125 action and merely constitute a means for regulating the action of the same and for preventing an excessive and unnecessary movement of the parts.

The arrangement of Figure 11 is there- 130

fore an example of a construction in which the shoes actually move radially to effect equalization; but the principle of operation may be maintained even if the bearing segments themselves are not capable of radial movement. Each bearing element may in effect be divided into component elements only one of which is mounted for radial movement. Such an arrangement as that last indicated is shown in Figures 12 and 13, in which the bearing segments or shoes 56 are loosely mounted in a radially fixed position between the shaft extension 57 and the flange 51. The shaft collar 49 is provided with radial slots to receive a series of wedge elements which take the form of sliding blocks 58 which are interposed between each shoe and the beveled surfaces 50 of the thrust collar slots. These blocks have considerable freedom of movement in a radial direction, and when the bearing is in operation they are subjected to centrifugal force which tends to move them radially outward in opposition to springs 60 to wedge them between each bearing shoe 56 and the inclined surface 50 of the thrust block. The shoes are thus forced axially into such positions as to equalize the thrust load upon them. Each block 58 is provided with a spherically faced lug 59 which permits the block and the associated shoe to tilt both tangentially and transversely with respect to the thrust collar 49 and the cooperating thrust block 47.

Figures 14 and 15 illustrate the application of the invention to a horizontal thrust bearing. The horizontal shaft which is designated 61 is provided with a thrust collar 62 and is mounted in a journal bearing 63. The thrust pressure is borne by bearing segments or shoes 64 which are arranged in two groups one on either side of the thrust collar. Each of the shoes has a wedge-shaped cross section and an inclined groove 65 in its back surface, and is mounted on a spherically faced stud 66 so that the shoes are free to tilt both transversely and tangentially; and in order that the load or end thrust may be equitably distributed over the annular bearing surfaces, it is only necessary that the shoes be subjected to substantially uniform radial pressures which will balance the opposed radial components of the reactive supporting pressures on the inclined faces of the grooves 65.

This distribution of the end thrust is effected, in the arrangement illustrated in Figure 14, by springs 67;—the springs for one row or set of shoes being provided with a spring equalizer reaction ring 68, and those of the other row or set of shoes being provided with a similar ring 69—and in order to compensate either wholly or partly for the unbalanced weight of the shoes on the upper and lower sides of the bearing, the

rings 68—69 are preferably mounted on a yielding spring support 70 which may evidently be so designed as to carry any desired portion of the vertical gravity pressures on the radially movable parts. 70

71 designates a scraper for distributing the oil, which is carried upwardly on the outer surface of the thrust collar, among the shoes at the top of the bearing.

The shoe supporting studs 66 are mounted 75 in the relatively stationary head members 72 and 73, that are connected by an interposed cylindrical housing member 74,—the parts being held in assembled position by the bolts 76 which extend through the lugs 80 75 on the housing member and engage the heads 72 and 73. Lugs 83 maintain the relative positions of the shoes and prevent them from rotating with the shaft.

The arrangement of Figure 16 corresponds to that of Figures 14 and 15 except that the bearing segments or shoes 77 are held loosely in a radially fixed position and are mounted on wedge blocks 78 which are pressed inwardly by springs 79 that serve 90 to equalize the pressure on the shoes. The springs react on a spring equalizer ring 80 which corresponds to the rings 68 and 69. 90

In the form here shown, studs 81 extend 95 through the housing member 74 and prevent the shoes from rotating about the shaft. Each shoe is provided with a spherical lug 82, which is seated on one of the wedge blocks 78 and permits the shoe to tilt both transversely and tangentially. 100

The weight of the wedge blocks 78 is considerably less than the weight of the shoes; and consequently the differences in the unbalanced gravity effects, due to the action of gravity on said blocks acting in conjunction with the springs in the upper part of the bearing and in opposition to the springs in the lower part of the bearing, in varying the thrust pressures on the segment bearing surfaces, are less than in the arrangement of Figures 14 and 15. 105

Referring to Figures 17 and 18, another horizontal thrust bearing structure is here shown in which the thrust collar 84 has a spherically curved bearing surface 85 with which a plurality of spherically-faced bearing segments or shoes 86 cooperate. Each of the shoes is pivotally mounted on the spherically curved end 87 of a bent-arm lever 88. Each lever is mounted on a transverse pivot 115 89 and has a weight 90 adjustably mounted on its rearwardly extending arm 91. The arrangement of parts is such that the weight 90 may be adjusted to counterbalance the weight of the shoe 86; and the position of the end 87 is such that the thrust pressure on the shoes tends to move all the weight arms 91 radially inward. This tendency is yieldingly opposed by springs 92 which are arranged to react on a spring equalizer ring 120 125 130

93 that is loosely supported on a stud 94 on the housing cap 95.

The effects of the springs 92 are equalized among themselves by the ring 93; and the 5 equalized spring pressures force the shoes to such positions that the load or end thrust is equitably distributed over the entire annular bearing surface between the shoes and the thrust collar.

10 It is evident that the weights, which are slidably mounted on screw-threaded extensions 96 of the lever arms, may be adjusted—in any suitable manner as by turning the nuts 97—to such positions as to exactly 15 counterbalance the weights of the shoes; or, if desired, they may be adjusted to such other positions as to throw a greater amount of the thrust on certain of the shoes, if desired. For example, it may be advantageous to make the shoes near the bottom 20 of the bearing sustain a greater thrust than those at the top; in which case the weights 90 are so adjusted as to unbalance the weights of the associated shoes.

25 Figures 19, 20 and 21 show a bearing structure embodying the present invention in which each of the bearing segments or shoes is mounted on a pair of spaced roller or rocker members which are of frustoco 30 conical form and are adapted to permit not only a radial equalizing movement of the shoes, but also a circumferential rolling of the shoes on the rockers to effect the desired tangential tilting of the segmental bearing 35 surfaces.

The arrangement of the base, shaft, thrust block, collar, and oil reservoir is similar to that of the Figure 1 structure, and corresponding parts are designated by the same 40 reference characters. The base is provided with a plurality of recesses in which the frustoco 45 conical rollers 98 are rotatively supported by the engagement of their trunnion projections 99 in suitable bearing sockets 100. The peripheral surfaces of these rollers—which engage with the conical or beveled faces 101 at the ends or radial edges of each shoe—are radially crowned to permit the 50 shoes to tilt radially or transversely on the roller supports.

By reason of the inclined engagement of the surfaces 101 with the conical surfaces of the rollers 98, the thrust pressure tends to press the shoes radially inward, and this 55 tendency is opposed by springs 102 which force the shoes radially outward and into such positions as to equitably distribute the thrust pressure among them.

Each of the rollers 98 may also be adjusted 60 in a radial direction by means of an adjusting screw 103 which is carried by a bearing bracket 104 suitably secured to the base ring 1. When the thrust collar 4 rotates in either direction, the shoes are moved 65 circumferentially—to a slight extent—in the

same direction, and are thereby tilted tangentially (in the manner explained more fully in my copending application Serial No. 240,761), thereby establishing wedge-shaped oil openings between the bearing 70 surfaces, which are characteristic of the Kingsbury thrust bearings.

The rollers are evidently called upon to rock through only a small angle, and in fact they may be more accurately termed 75 rockers in view of the function which they perform. It is therefore possible to substitute for each of the complete rollers 98 a segment or rocker member 105 as shown in Figures 23 and 24.

80 It is evident that the inclination of the rockers may be reversed so that the thrust pressure tends to move the shoes away from the shaft instead of towards it. In that case the equalizing springs will be arranged as in 85 Figure 1.

The bearing segments or shoes may be held against radial displacement by lugs 106 as shown in Figure 22; in which case the rollers are radially movable and provided with adjustable springs 108 which serve the same purpose as the springs 102 in equalizing the pressure on the shoes; it being, of course, understood that with this arrangement the thrust pressure tends to 95 press the shoes inwardly against the studs 106, and the rollers outwardly against the tension of the springs 108. The adjusting screws 107 may be utilized to manually adjust or equalize the spring pressures, but 100 they are obviously not essential and may be omitted if desired, or replaced by a common spring equalizer ring, such as that indicated by 16 or 16^a in Figures 1 and 7.

105 In the structure of Figures 25, 26 and 27 the base is provided with spherically curved grooves 109 which are disposed at right angles to the median radial planes of the bearing segments or shoe members 112. Each groove contains two bearing balls 110 that 110 are separated by a spacing ball 111. Each shoe is provided on its lower surface with a pair of beveled or conical surfaces 114 which are inclined to the axis of the shaft and so spaced as to engage the upper surfaces of the bearing balls 110; the arrangement of parts being such that the thrust pressure tends to move the shoes radially outward. This tendency is opposed by flat 115 springs 115; or some other suitable yielding means. This construction—like that previously described—not only effects the equitable circumferential distribution of the load on the annular bearing surfaces by the action of the spring equalizing means; but 125 also permits each shoe to tilt radially on the spherical surfaces of the ball supports 110; while the desired circumferential or tangential tilting of the bearing segments is secured by a slight longitudinal rolling 130

movement of the shoes on these same supports.

The supporting rollers may be frusto-conical and the bottom surfaces of the bearing segments or shoes so shaped as to engage therewith over the entire length of the frusto-conical faces if the shoe is made in sections so that one of the sections may tilt radially relative to the other section. An arrangement of this kind is shown in Figures 28, 29 and 30. In this construction, frusto-conical rollers 116 are maintained in spaced relation on the upper surface of a flat base ring by means of a cage 117 having inclined radial bolts or pins 118 on which the rollers are rotatively mounted.

In the form here shown, the shoes which are designated 119 are composed of a bottom section 120 having a conical lower surface 121 that is inclined to the axis of the bearing (as clearly shown in Figure 28) and a top section 122 which is mounted on the bottom section 120 and has a cylindrical face 123 that is seated in a correspondingly curved recess in the bottom section.

Each of the two-part shoes acts as a unit in tilting tangentially to establish a wedge-shaped oil film when the shoe members roll circumferentially on the cone supports 116; and the upper section of each shoe is free to tilt radially or transversely to equalize the pressure on the inner and outer zones of the shoe surface. The tendency of the end thrust is to move the shoes radially inward on the upper downwardly inclined surfaces of the rollers 116, and this tendency is opposed by the springs 125 which act, as before, to circumferentially equalize or equitably distribute the load over the entire annular surface of thrust bearing engagement.

Figures 31 and 32 illustrate a slightly modified structure in which the bearing segments or shoes are replaced by a flexible annular bearing member 126, the sectors of which are connected by flexible webs 127. Each of these bearing sectors or segments is provided with a cylindrical lug 128 which corresponds to the lug 123; and the ring member 126 is supported as a whole on a plurality of blocks 129 that are shaped to correspond to the blocks 120 and are similarly mounted on rollers 130. In this arrangement however, the bearing structure is necessarily held against radial movement; and the equalization is effected by springs 131 which act on the rollers; the cage 132 being formed to permit of a movement of the rollers in a radial direction. Furthermore, in the form here shown, the pins on which the rollers are mounted have enlargements 133 at their outer ends which are screw-threaded into the cage so that they may be adjusted to vary the tension of each of the equalizing springs, as may be de-

sired. Springs 134 may be introduced between the ring 126 and the blocks 129 to assist in supporting the edge zones of the sectors 126 and prevent the crowning of the flexible bearing surfaces.

In Figures 33 and 34 I have shown another structure in which each bearing segment or shoe is formed in two parts, 135 and 136, which have cooperating surfaces that are inclined in a radial direction and are curved in a circumferential direction. In other words, their adjacent surfaces are conically curved, the arrangement being such that the thrust pressure tends to make the upper section 135 move inwardly and the lower section 136 move outwardly. Each lower section has a cylindrical bottom surface which permits the shoe to rock transversely, as a whole; but it is mounted loosely in a pocket 137 in the base ring, so that only the upper section can move transversely or radially in response to the end thrust pressure. This radial movement is opposed by radial equalizing springs 138 mounted in pockets 139 between the shoe sections. The upper section of the shoe may tilt tangentially relative to the lower section to establish a wedge-shaped oil film between the bearing surfaces; ball bearings 140 being preferably introduced to make the upper section rock more easily.

Another two-part shoe structure is shown in Figure 35; in this construction the two-part shoes, with their conically curved cooperating surfaces, form a part of the rotatable member of the bearing and tension springs 141 are utilized for the purpose of opposing movement of the lower shoe sections or elements with respect to the upper elements thereof under the action of centrifugal force, upon which the equitable distribution of the pressure on the bearing segments depends.

In Figures 36 and 37 I have shown another two-part shoe construction in which the lower shoe elements 142 are mounted to rock or tilt circumferentially on radial ribs 143; and the upper cooperating elements 144 are mounted to rock radially on the tangentially disposed ribs 145. The upper elements also tend to slide radially with respect to the lower elements by reason of the end thrust pressure, and springs 146 are interposed between the elements to effect the annular equalization of the load on the bearing surfaces.

While I have shown a number of different structures which embody my invention, it is evident that it is not limited to any one or all of the forms shown and described. Thus it is evident that embodiments of my invention illustrated as applied only to vertical bearings are applicable to horizontal bearings and vice versa; and that the radially movable equalizing instrumentalities may

be applied to either rotatable or stationary members of the bearing. My present invention is concerned primarily with the equalization of pressure by the radial movement of portions of the cooperating bearing members, but there are disclosed in the structures illustrated a number of novel features which form the subject matter of other applications.

10. What I claim is:

1. In a thrust bearing, the combination of relatively rotatable thrust members, and means dependent on centrifugal action for equitably distributing the pressure thereon.

15. 2. In a thrust bearing, the combination with a rotatable member, of a plurality of bearing segments associated therewith; and automatic means dependent on radial pressure for equitably distributing the pressure 20 on the segments.

25. 3. In a thrust bearing, the combination with a rotatable member, of a plurality of bearing segments associated therewith, and radially adjustable means for automatically effecting an equitable distribution of pressure 30 on the bearing members.

35. 4. In a thrust bearing of the tiltable shoe type, radially movable means for automatically distributing the pressure on the several shoes.

40. 5. In a thrust bearing of the tiltable shoe type, centrifugally operated means for equitably distributing the pressure on the several shoes.

45. 6. In a thrust bearing, the combination of relatively movable members, and means automatically operated by a radial component of the thrust pressure for equitably distributing the pressure thereon.

50. 7. In a thrust bearing, the combination of a plurality of bearing segments so arranged that a component of the thrust pressure tends to produce radial movement and centrifugal force tends to oppose said movement.

55. 8. In a thrust bearing, the combination of a plurality of bearing segments so arranged that a component of the thrust pressure tends to produce radial movement, and means whereby such movement is opposed to equalize the pressure.

60. 9. In a thrust bearing, the combination of a plurality of bearing segments so arranged that a component of the thrust pressure tends to produce radial movement, and springs coacting therewith to effect an equitable distribution of pressure on said segments.

65. 10. In a thrust bearing, the combination of a plurality of bearing segments having inclined surfaces so arranged that the thrust pressure tends to effect radial displacement, and means whereby said displacement is automatically opposed to effect equitable

distribution of the pressure on said segments.

11. In a thrust bearing, the combination of a plurality of bearing elements mounted on the rotor member of the bearing and having inclined surfaces so arranged that the thrust pressure tends to move the elements radially inward in opposition to centrifugal force, whereby the latter acts to equalize the pressure on the elements when the bearing is in operation.

75. 12. In a thrust bearing, the combination of a plurality of bearing elements, means for supporting the elements in such manner that the thrust pressure tends to move the elements radially, and resilient means coacting with said elements.

13. In a thrust bearing, the combination of a plurality of bearing elements, means for supporting the elements in such manner that the thrust pressure tends to move 85 the elements radially, and means whereby the elements are held in equitable pressure engagement with the cooperating bearing surface.

90. 14. The combination of a bearing member having an annular bearing surface, a plurality of wedges for equitably distributing the end thrust pressure on the said annular surface, and a spring for each wedge.

95. 15. The combination of a bearing member having an annular bearing surface, a plurality of wedges for equalizing the end thrust pressure on the said bearing surface, and means whereby said wedges are automatically operated.

100. 16. In a thrust bearing, the combination of a plurality of bearing segments, means for holding the segments against radial movement, and means dependent on centrifugal action for equitably distributing the pressure on said segments by relative axial displacement.

110. 17. In a thrust bearing, the combination of a plurality of bearing segments, means for holding the segments against radial movement, and radially movable means for automatically effecting an equitable distribution of pressure on said segments by relative axial displacement.

115. 18. In a thrust bearing, the combination of a rotatable bearing member, a plurality of bearing elements mounted thereon and provided with inclined surfaces so arranged that the thrust pressure tends to move the elements inward in opposition to the centrifugal action due to the rotation of the member, and springs for restricting the outward movement due to the centrifugal action.

120. 19. In a thrust bearing, the combination of a rotatable bearing member, a plurality of bearing elements mounted thereon and having inclined surfaces so arranged that the thrust pressure tends to move the ele-

- ments inward in opposition to the centrifugal action due to the rotation of the member, springs for restricting the movement of the elements, a relatively stationary bearing member cooperating with said rotatable bearing member, and a universal rocking support for the said stationary member. 5
20. In a thrust bearing, the combination of a rotatable thrust collar having radial grooves provided with inclined bottom surfaces, a series of wedge blocks movably mounted in said grooves, and a plurality of bearing segments supported by the said wedge blocks. 10
15. 21. In a thrust bearing, the combination of a rotatable thrust collar having radial grooves provided with inclined bottom surfaces, wedge blocks movably mounted in said grooves, a plurality of bearing segments supported on the movable wedge blocks, and means for holding the segments against radial movement. 20
25. 22. In a thrust bearing, the combination of a rotatable thrust collar having radial grooves provided with inclined bottom surfaces, movable wedge blocks mounted in said grooves, a plurality of bearing segments supported on the movable wedge blocks, means for holding the segments against radial movement, and yielding means for limiting the radial movement of the wedge blocks in the thrust collar grooves. 30
35. 23. In a thrust bearing, the combination of relatively rotatable bearing members, one of which comprises a plurality of tiltable bearing segments, and means dependent on the centrifugal action of the rotatable member for equalizing the load on the bearing segments. 35
40. 24. A thrust bearing comprising an annular relatively stationary bearing member, a rotatable member having tilttable bearing segments mounted thereon, and means actuated by centrifugal force for effecting an equitable distribution of the load over the annular surface of bearing engagement. 45
45. 25. A thrust bearing comprising a rotatable member, a plurality of bearing segments associated therewith, and means dependent upon the centrifugal action due to the rotation of said segments for equitably distributing the pressure on the same. 50
55. 26. A thrust bearing comprising a rotatable member, a plurality of tilttable bearing segments, and interposed radially movable wedges adapted to be actuated by centrifugal force for distributing the pressure on said bearing segments. 55
60. 27. A thrust bearing comprising a plurality of tilttable bearing shoes, and wedge-shaped shoe supports actuated by the centrifugal force produced by the rotation of the said supports. 60
28. In a thrust bearing, relatively rotatable bearing members comprising a plurality of bearing elements movable by centrifugal force to equitably distribute the bearing pressure on said members. 65
29. In a thrust bearing, relatively rotatable bearing members comprising a plurality of bearing elements automatically movable in radial directions to equitably distribute the bearing pressure on said members. 70
30. A bearing member including a plurality of bearing segments, and means intermediate said member and segments whereby a transverse component of the pressure thereon is utilized for effecting an equitable distribution of the pressure on said segments. 75
31. A bearing member including one or more bearing segments and means intermediate said member and segments whereby the bearing pressure on said segments tends to move the same radially with respect to said member. 80
32. In a thrust bearing, a bearing member comprising a plurality of tilttable bearing elements mounted to move automatically in radial directions to equitably distribute the bearing pressure on said elements. 90
33. In a thrust bearing, a bearing member comprising a plurality of tiltably-mounted bearing elements movable in response to centrifugal force to equitably distribute the bearing pressure on said elements. 95
34. In a thrust bearing, a plurality of bearing elements and means mounting said elements whereby they may move radially in response to a radial component of the bearing pressure thereon. 100
35. In a thrust bearing, a plurality of bearing elements and means mounting said elements whereby they may move radially in response to centrifugal force. 105
36. In a thrust bearing, a plurality of bearing elements and means mounting said elements whereby they tend to move inwardly in response to a radial component of the bearing pressure and may move outwardly in response to centrifugal force. 110
37. In a thrust bearing, a stationary bearing member and a rotatable bearing member, one of said members comprising a plurality of bearing elements movable radially in response to the bearing pressure between said members to equitably distribute the bearing pressure thereon. 115
38. In a thrust bearing, a stationary bearing member and a rotatable bearing member comprising a plurality of bearing elements movable radially in response to centrifugal force to equitably distribute the bearing pressure on said elements. 120
39. In a thrust bearing, a stationary bearing member and a rotatable bearing member

comprising a plurality of bearing elements movable radially in response to centrifugal force to equitably distribute the bearing pressure on said elements, and resilient means opposing said movement of said elements.

40. In a thrust bearing, a stationary bearing member and a rotatable bearing member, one of said members comprising axially inclined faces, and bearing elements engaging said inclined faces and wedged by coaction therewith into positions wherein the bearing pressure is equitably distributed on said elements.

41. In a thrust bearing, a stationary bearing member and a rotatable bearing member, one of said members comprising axially inclined faces, and bearing elements mounted to move in response to centrifugal force and engaging said inclined faces to be wedged by coaction therewith and in opposition to centrifugal force into positions wherein the bearing pressure is equitably distributed on said elements.

42. The method of equitably distributing the bearing pressure on the bearing segments of a bearing which comprises mounting said segments so that the bearing pressure thereon tends to produce radial movement, and opposing such movement by a radial force.

43. The method of equitably distributing the bearing pressure on the bearing segments of a bearing which comprises mounting said segments so that the bearing pressure thereon has a transverse component, and opposing said component by a transverse force which permits relative movement of said segments to positions wherein the pressure thereon is equitably distributed.

44. The method of equitably distributing the bearing pressure on the bearing segments of a bearing which comprises mounting said segments so that the bearing pressure tends to wedge said segments radially, and opposing said movement of said segments by a radial force which tends to maintain said segments in bearing engagement.

45. The method of equitably distributing the bearing pressure on the bearing segments of a bearing which comprises mounting said segments on a rotatable member so that the bearing pressure thereon tends to produce radial movement, and opposing such movement by centrifugal force.

46. In a thrust bearing, a bearing member having one or more axially inclined faces, bearing segments, and radially movable elements automatically coacting with said inclined faces and segments to effect an equitable distribution of pressure on said segments.

47. In a thrust bearing, a bearing member having one or more axially inclined

faces, bearing segments, and elements radially movable in response to centrifugal force and coacting with said inclined faces and segments to effect an equitable distribution of pressure on said segments.

48. In a thrust bearing, a bearing member having one or more inclined faces, bearing segments opposed thereto, and wedge elements cooperating with said inclined faces and movable radially under a radial component of the bearing pressure, said elements cooperating with said segments to wedge the same into positions wherein the bearing pressure thereon is equitably distributed.

49. In a thrust bearing, a bearing member having one or more inclined faces, bearing segments opposed thereto, and wedge elements cooperating with said inclined faces and movable radially under a radial component of the bearing pressure, said elements also being mounted to move radially in response to centrifugal force and cooperating with said segments to equitably distribute the pressure thereon.

50. In a thrust bearing, a bearing member having one or more inclined faces, bearing segments opposed thereto, and wedge elements intermediate said member and segments and tiltably mounting said segments, said wedge elements being automatically movable in radial directions to equitably distribute the pressure on said segments.

51. In a bearing, the combination of a bearing member comprising a plurality of bearing segments, a plurality of wedge elements on which said segments are tiltably mounted, and springs coacting with said wedge elements.

52. In a bearing, the combination of a plurality of bearing segments and a plurality of radially movable wedge elements supporting said segments and automatically operative to equitably distribute the pressure thereon.

53. In a bearing, the combination of a supporting member, a series of wedge elements movably mounted on said supporting member, and a plurality of bearing segments tiltably mounted on said wedge elements, at least one of the surfaces coacting with each of said wedge elements being inclined.

54. In a bearing, the combination of relatively rotatable bearing members at least one of which comprises a plurality of two-part bearing segments, the parts of said segments being relatively movable in response to a transverse component of the bearing pressure to effect an equitable distribution of the bearing pressure on said segments.

55. In a bearing, the combination of relatively rotatable bearing members at least one of which comprises a plurality of two-part

bearing segments, the parts of said segments being relatively movable in response to a transverse component of the bearing pressure to effect an equitable distribution of the bearing pressure on said segments, and resilient means opposing relative movement of said segment parts.

56. In a bearing, relatively rotatable bearing members including a plurality of bearing segments, and means mounting said segments whereby they tend to move in response to a transverse component of the bearing pressure to equitably distribute the pressure on said segments.

57. In a bearing, relatively rotatable bearing members including a plurality of bearing segments, means mounting said segments whereby they tend to move in response to a transverse component of the bearing pressure to equitably distribute the pressure on said segments, and resilient means opposing said movement.

58. In a bearing, relatively rotatable bearing members including a plurality of bearing segments cooperating with said members through axially inclined surfaces whereby they tend to move in response to a transverse component of the bearing pressure, and means utilizing said transverse pressure to effect an equitable distribution of the bearing pressure on said segments.

59. In a bearing, the combination of a bearing member comprising a plurality of bearing segments, a plurality of wedge elements supporting said segments, and resil-

ient means opposing relative movement of said segments and elements.

60. In a bearing, the combination of relatively rotatable bearing members including a plurality of bearing segments, means mounting said segments whereby they tend to move transversely in response to a transverse component of the bearing pressure, and resilient means coating therewith to equitably distribute the pressure on said segments.

61. In a bearing, the combination of a stationary bearing member, and a relatively rotatable bearing member including a plurality of bearing segments, each of said segments cooperating with an axially inclined surface on said rotatable member whereby relative axial movement of said segments and rotatable member is effected by the action of centrifugal force.

62. In a bearing, the combination of a stationary bearing member, a relatively rotatable bearing member including a plurality of bearing segments, each of said segments cooperating with an axially inclined surface on said rotatable member whereby relative axial movement of said segments and rotatable member is effected by the action of centrifugal force, and resilient means cooperating with said segments in opposition to centrifugal force.

In witness whereof, I have hereunto set my hand this 29th day of May, 1918.

FRANK L. O. WADSWORTH.
